APPARATUS FOR INFLATING AND DEFLATING AN EXPANSIBLE PLUG BY MEANS OF A LIQUID CONTENT

Edward T. Ahern, New Haven, Conn.; Irene D. Ahern, administratrix of said Edward T. Ahern, deceased

Application August 25, 1942, Serial No. 456,020

3 Claims. (Cl. 138—93)

This invention relates to means for inflating and deflating an expansible plug within a laterally walled enclosure by means of a liquid content.

The objects of the invention are to provide, in connection with an expansible receptacle or plug, an inflation means employing a nearly incompressible liquid content; to provide such a receptacle or plug with a pipe connection having a fluid way normally open to the atmosphere; and to provide for such apparatus a reversibly connectible tubular member having a fluid way in one direction only and adapted for an alternate connection to the apparatus with its fluid way open toward the receptacle or plug, or with its fluid way open in the opposite direction to exhaust the liquid content of the receptacle.

With reference to the accompanying drawing, the Figure 1 is an upright view of the device, illustrating the two parts thereof, of which one part is shown in relative position for interconnection for an inflating operation; and the Figure 2 is an upright view of one part of the two-part device with a fragmentary portion of the other part in relative position therewith for an interconnection for a deflating operation.

Referring more particularly to the accompanying drawing, the apparatus for inflating and deflating an expansible receptacle or plug, by means of a liquid content, comprises a cylindrical container or reservoir 1 openable at both ends 1A and 1B of which the end 1B is interiorly communicated with the interior of an elongated tubular member 2 having an end 2A connected thereto, the opposite end 1A of the container 1 being provided with a one-way valve 3 which opens a fluid way from the container 1 in an upward direction to the atmosphere. A side wall of the container 1 is provided with a perforation 4 communicating with the interior of a second tubular member 5 which is secured thereto, the opposite extremity of the tubular member 5 being provided with a coupling member 6. The tubular member 2 is permanently closed at its free end 2B, but is provided within its side wall with a perforation 2C adjacent its free extremity 2B. A receptacle or plug 7 having an open end 7A, and being of an expansible or incompressible material, is drawn over said free extremity 2B, the said open end 7A being securely bound around the free ex-

tremity 2B so as to enclose within the receptacle 7 said free extremity 2B and its wall perforation 2C. A compressible hollow bulb 8 of which both ends 8A and 8B are open has each opening provided with a one-way valve, 9 and 10 respectively, which together provide a fluid way through the bulb 8 in one and the same direction. Each of said openings, at 8A and 8B, thus provided with the valve 9 and 10, communicates with the interior of portions 11 and 12 of the tubular member having permanent connection with the bulb 8 and to the free end of each tubular member portion 11 and 12 is provided a coupling member 13 and 14 respectively, each coupling member 13 and 14 being adapted for an alternate connection with the coupling member 6 of the tubular member 5 of the container 1. The outlet 3A of the one-way valve 3 is exteriorly threaded, as at 3B, and a cap 3C, provided with an internal thread is adapted to be screwed down over the outlet 3A whenever desired.

In operation, when it is desired to inflate the plug 7 with a liquid content 16, the bulb 8 section of the apparatus is connected to the other section by means of the couplings 6 and 13, and the free coupling 14 end is deposited within a source of liquid supply. With each manual pressure to collapse the bulb 8, and thereby cause a partial vacuum therein, a thumb of the other hand of the operator is simultaneously placed over the outlet 3A of the valve 3 to prevent the escape of air or water therefrom during such intervals of pressure. Due to the resilient rebound of the construction of the bulb 8 it reacts, upon the release of manual pressure, to automatically return to its normal rounded contour, but can do so only as the partial vacuum or suction draws therein a liquid (preferably water) content from the source of supply; for the valve 9 is then closed while the valve 10 alone is open to permit a flow of water from the source of supply to enter the bulb 8. Subsequent manual applications of pressure on the bulb 8, accompanied by the simultaneous placing of the thumb over the outlet 3A of the valve 3, closes the valve 10 against the backward flow of the water content of the bulb 8, but the valve 9 opens with the passage therethrough of such water content which continues to cause it to enter, by way of the tubular member 5, into the container 1. The law of gravity, together

with bulb pressure, causes the water content of the container 1 to flow down within the tubular member 2, out through the perforation 2C and into the plug 7 to inflate the plug from the collapsed plug position 7C to the inflated position 10 of the plug 7 illustrated in full line in Figure 1 or to any plugging degree limited only by the inside diameter 15 of a pipe, or other laterally walled enclosure, into which the receptacle is placed and of course, the strength of the material of which the plug 7 is made.

For the deflating operation of the apparatus, the bulb 8 section is reversed relative to the container 1, by disconnecting the couplings 6 and 13 and connecting the couplings 14 and 6. In this reversed position of the bulb 8 section relative to the container 1 manual pressure upon the bulb 8 will permit escape of air within the bulb 8, by way of the valve 9, through the tubular member 11 and out at the idle coupling member 13, but by force of suction, upon the release of manual pressure on the bulb 8, the valve 10 will open to permit the flow of water content from the plug 7 into the bulb 8. Each of the subsequent applications of pressure upon the bulb 8 will cause a closed valve 10 and an open valve 9 to permit the water content of each filling of the bulb 8 to flow through the tubular member 11 and out at the idle coupling member 13.

It is to be noted, when operating the apparatus as an inflater, that, while the thumb of the operator is not resting upon the outlet 3A of the valve 3 and no pressure is being applied to the bulb 8, the valve 3 is openable to the atmosphere by means of pressure from within thereby giving the opportunity for any air, admitted within the tube 2 or plug 7 at the time of the initial manual pressure upon the bulb 8, to escape therethrough. Air in plug 7 may rise within tube 2 through the perforation 4A, provided in the side wall of the upper portion of the plug-covered lower portion of the tubular member 2, as the water content fills up the plug 7. But when undue pressure against opposite sides of the plug 7 is had, by reason of over filling and contact with the side walls of its enclosure, such water content thereby will be forced up through the tubular member 2 and out at the outlet 3A of the valve 3. When this happens, it constitutes a signal to the operator to discontinue the inflating operation.

But when the receptacle or plug 7 is made of incompressible material, or of a thick compressible material, the inflation thereof is accomplished as has been described, with the exception that the repeated manual pressure upon the bulb 8 is made until the water is forced out at the outlet 3A of the one-way valve 3. Then the cap 3C may be placed over the outlet 3A and screwed down thereon, and the manual pressure upon the bulb 8 continued for a few times to positively inflate the plug 7 to a firm plugging degree.

The advantages of inflating a plug by means of a liquid content, rather than by air or gas, are many. Not among the least is that of a liquid expanded plug being adapted to be left with a fluid way open to the atmosphere, the plug thus expanded being self-retaining. The weight of a partially expanded plug, having a liquid content, may greatly facilitate the placing of the plug in a desired location within a laterally walled enclosure before final expansion to a plugging degree. And further, a plug expanded by means of a liquid content is bound to provide a more solid plugging contact adapted to support the weight of any cleaning solution that may be in-

serted within the laterally walled enclosure above the plugged location.

With a plug inflated by means of a liquid content as compared with the same plug inflated by means of air or gas:

A lesser pound pressure is required with a liquid content;

A greater thickness of plug material may be safely employed with a liquid content;

During an inflating operation, if an excess water pressure were placed on the inflated plug at a plugging location, which excess pressure could occur only if the cap 3C were screwed down upon the outlet 3A of the valve 3, the only resultant damage would be the bursting of the plug and possibly the loss of cleaning solution which would pass off below;

If, however, excess air pressure had been used in the inflating of the plug, and cleansing solution had been placed over the plugged location, and the plug had burst by reason of excess pressure of air, or because punctured in any way, the resultant effect might prove serious as the suddenly released air might force upwardly any cleaning solution, that may have been supported by the plug, into the face of the operator, as well as spattering walls and ceiling.

I claim:

1. An apparatus for inflating and deflating an inflatable plug within a conduit by means of a water content, the apparatus comprising a two-member device of which the main member is an elongated tube having at one extremity a coupling means; a bag connected to the opposite extremity of said tube for insertion within the conduit to be plugged; a bodily reversible tube constituting the second member; coupling means with which the reversible member is provided at both ends; means positioned intermediate within the reversible member to establish, upon the connection of one of its coupling means with the coupling means of the main member, a one-way fluid passage through the connected apparatus to and within said bag and, upon the bodily reversal of the reversible member and connection of its opposite coupling means with that of the main member, a one-way fluid passage through the connected apparatus from said bag; and means adapted to force 50 a flow of water therethrough, the idle extremity of the second member being associated with a water supply.

2. An apparatus for inflating and deflating an inflatable plug within a conduit by means of a water content, the apparatus comprising in combination a fitting having run openings in axial alignment and also a branch opening therein; a one-way valve openable to the atmosphere upon pressure from within and provided by one of the axially aligned openings; a cap removably secured to said valved opening; an elongated tube connected at one end of the other axially aligned opening; a bag connected to the free end of said tube for insertion within a conduit to be plugged; a tube connected by one end with, and extending, said branch opening and having coupling means carried by the free end thereof; a separate bodily reversible tube member having at both ends a coupling means adapted for alternate connection with the coupling means of the branch tube, the idle end being associated with a water supply; means inserted intermediately within the reversible member to establish, upon the connec-

tion of the coupling means of the branch tube with the coupling means at one end of the reversible member, a one-way fluid passage therein to and within said bag and, upon bodily reversal of said member in its connection with said branch tube, a one-way fluid passage from said bag; and means adapted to force a flow of water therethrough.

3. An apparatus for inflating and deflating an inflatable plug within a conduit by means of a water content, the apparatus comprising in combination a fitting having run openings in axial alignment and also a branch opening therein; a one-way valve openable to the atmosphere upon pressure from within and provided by one of the axially aligned openings; a cap removably secured to said valved opening; an elongated tube connected at one end of the other axially aligned opening; a bag connected to the free end of said tube for insertion within a conduit to be plugged; 10

15

20

a tube connected by one end with, and extending, said branch opening and having coupling means carried by the free end thereof; a separate bodily reversible tube member having at both ends a coupling means adapted for alternate connection with the coupling means of the branch tube, the idle end being associated with a water supply; a compressible bulb inserted intermediately within the reversible tube member, said bulb having at each end thereof a one-way valve openable in one and the same direction to establish, upon the connection of the coupling means of the branch tube with the coupling means at one end of the reversible member, a one-way fluid passage therein to and within said bag and, upon the bodily reversal of said member in its connection with said branch tube, a one-way fluid passage from said bag.
